CLAIM

The ornamental design for a windmill cork holder, as shown and described.

DESCRIPTION

FIG. 1 is a front, right side and top perspective view of a windmill cork holder showing my new design;

FIG. 2 is a back, bottom and left side perspective view thereof;

FIG. 3 is a right side view thereof;

FIG. 4 is a front view thereof; and,

FIG. 5 is a back view thereof.

The broken lines define the bounds of the claimed design and form no part thereof.
